UNITED STATES PATENT OFFICE.

JOSEPH B. STRAUSS, OF CHICAGO, ILLINOIS.

INCLOSING DEVICE FOR FLYING MACHINES.

Application filed August 10, 1920. Serial No. 402,645.

To all whom it may concern:

Be it known that I, JOSEPH B. STRAUSS, a citizen of the United States, residing at Chicago, in the county of Cook and State 5 of Illinois, have invented a certain new and useful Improvement in Inclosing Devices for Flying Machines, of which the following is a specification.

This invention relates to inclosing devices 10 for flying machines, etc., and has for its object to provide a new and improved device of this description. The invention has among other objects to provide a structure of the kind described having means 15 for easily and quickly opening and closing a portion of the structure so as to permit the devices which it houses to be easily inserted and removed. The invention has other objects which are more specifically 20 pointed out in the following description.

Referring now to the drawings—

Fig. 1 is a front view showing one form 25 of housing device embodying the invention;

Fig. 2 is a section through the door and 30 the portions of the housing device adjacent thereto;

Fig. 3 is a sectional view taken on line 3—3 of Fig. 2.

Fig. 4 is a view showing a modified construction.

Like numerals refer to like parts throughout the several figures.

Referring now to the drawings I have shown in Fig. 1 a front view of a housing 35 device 1. This housing device is provided with a door 2 which may be opened and closed when the device housed is taken in or out. The door 2 works on horizontal pivots and moves vertically to open and close it. 40 As herein shown the door is provided with a plurality of trusses 3, and is supported by pins 4 which are connected with the trusses and which also project through the supporting pieces 5 which are fastened to the 45 supporting beams 6. Any desired number of trusses and supporting beams may be used, and in the construction shown I have illustrated four. The trusses are provided with projecting ends 7 which project beyond the pivotal points, that is the pins 4.

These projecting ends may project between the beams 6 as shown for example in Figs. 2 and 3. A counterweight 8 is attached to the projecting rear ends of the trusses by 50 pins 19. This counterweight is also connected by links 10 with a fixed part of the

structure, as for example by means of the pivots 11. The links are also pivoted to the counterweight by the pivots 12. The counterweight preferably counterbalances 60 the door so that it is balanced in all its various positions and moves with the door. The position of the counterweight is shown in Fig. 2 in full lines when the door is 65 opened, and in dotted lines when the door is closed. Some suitable means is provided for opening and closing the door. As herein shown a motor 13 is provided. This motor is connected with suitable gearing 70 14 and a shaft 15, having a plurality of 75 pinions 16 which engage the racks 17 on the trusses. The door may also be operated by hand by means of a chain or the like 18, passing over a wheel on the shaft 20. When this chain is pulled it rotates the shaft 20 80 and the gear 14 so as to open or close the door. There may be a chain at each side of the door if desired. The motor may be operated by means of the motor starter 21. I prefer to provide a groove 22 in the floor 85 23 at a point just below the end of the door when the door is closed, and in this groove I prefer to provide a heating device, such as a steam pipe 24, so that any snow and sleet or the like that might otherwise obstruct the closing of the door will be melted 90 so as to leave the space for the end of the door always clear.

The device is particularly adapted for large structures and by this means the door, 95 regardless of its size and weight, can be easily handled because of its construction, its method of suspension and its counter-weight arrangement.

When the door is open it forms a canopy, 95 thus increasing the protective space and the space under which operators can work and still be protected or under cover.

In Fig. 4 I have shown a construction 100 where there are two doors or sections 27 and 28, one opening upward and the other opening downward. Both of these doors are counter-balanced as shown. The upper door is provided with pivots 27^a and when opened acts as a canopy and the lower door when opened acts as the roadway or extended floor upon which the devices to be enclosed may be moved as they are being moved into the enclosure. When two doors are used, that is where the device is divided 105 into an upper and lower section, the upper section may be mounted and arranged as 110

shown in Figs. 2 and 4. The lower section 28 has its pivots 29 supported by supports 30, and a counterweight 31 is pivoted to the door and operates in a pit 32. These sections it will be noted have extensions beyond the pivots and the counterweights are connected with these extensions. A space 33 is provided for the lower section when open so that it may act as a runway. The inner 10 face 34 of this door is provided with a suitable covering so that it may act as a floor or runway when in its open position. It will be noted that when the door is opened all of the parts are beyond the limits of the 15 clearance line of the openings to be closed, which is a line running crosswise of the opening at the upper and lower part thereof, forming the limits vertically of the maximum opening.

20 I have described in detail a particular construction embodying the invention but it is of course evident that the parts may be varied in many particulars, without departing from the spirit of the invention as set forth in the claims hereto appended and I therefore do not limit myself to the particular construction shown.

I claim:

1. A housing device for flying machines 30 comprising an inclosing device provided with an opening through which the object to be housed may be introduced into and withdrawn from the inclosing device, a door for said opening pivoted near its upper 35 end and normally in a vertical position when closed said door opening outwardly, a portion of said door projecting beyond the pivotal point, and a counterweight connected with the projecting end of said door arranged to counter-balance the same, the portion of the door projecting beyond the pivotal point, and the counterweight, projecting into the interior of the inclosing device, so as to be enclosed and housed thereby.

45 2. A housing device for flying machines comprising an inclosing device provided with an opening through which the object to be housed may be introduced into and withdrawn from the inclosing device, a door for said opening pivoted near its upper 50 end and normally in a vertical position when closed said door opening outwardly, a portion of said door projecting beyond the pivotal point, and a counterweight connected 55 with the projecting end of said door arranged to counter-balance the same, the portion of the door projecting beyond the pivotal point, and the counterweight, projecting into the interior of the inclosing device, so as to be enclosed and housed thereby, and means for moving said door and said counterweight to open and close said opening.

3. A housing device for flying machines comprising an inclosing device provided

with an opening through which the object to be housed may be introduced into and withdrawn from the inclosing device, a door for said opening, said door opening outwardly and provided with a plurality of trusses 70 spaced apart, a support for said door, pivots pivotally connecting said trusses with said supports, a portion of said trusses projecting beyond said pivots, a rack connected with one of said trusses, a pinion engaging 75 said rack, a motor operatively connected with said pinion, and a counterweight connected with the projecting ends of said trusses, the portion of the door projecting beyond the pivotal point, and the counterweight, projecting into the interior of the inclosing device so as to be enclosed and housed thereby.

4. A housing device for flying machines comprising an inclosing device provided 85 with an opening through which the object to be housed may be introduced into and withdrawn from the inclosing device, a door for said opening, said door provided with a plurality of trusses spaced apart, a support 90 for said door, pivots pivotally connecting said trusses with said supports, a portion of said trusses projecting beyond said pivots, a counterweight pivoted to the projecting 95 ends of said trusses, and a pivotal connection between said counterweight and a fixed part at a distance therefrom.

5. A housing device for flying machines comprising an inclosing device provided with an opening through which the flying 100 machine to be housed may be introduced into and withdrawn from the inclosing device, a door for said opening pivoted near one end and normally in a vertical position when closed, a portion of said door projecting 105 beyond the pivotal point, and a counterweight connected with said projecting end of said door arranged to counter-balance the same, said door when opened being substantially in a horizontal position.

6. A housing device for flying machines comprising an inclosing device provided with an opening through which the object to be housed may be introduced into and withdrawn from the inclosing device, a door for said opening, said door provided with a plurality of trusses spaced apart, supports for said door arranged in pairs and spaced apart, the ends of said trusses passing freely between the supports of each pair, pivots 115 connected with said trusses at a distance from their ends, said pivots connecting the trusses with said supports.

7. A housing device for flying machines comprising an inclosing device provided with 125 an opening through which the object to be housed may be introduced into and withdrawn from the inclosing device, a door for said opening, said door provided with a plurality of trusses spaced apart, supports 130

for said door arranged in pairs and spaced apart, the ends of said trusses passing freely between the supports of each pair, pivots connected with said trusses at a distance 5 from their ends, said pivots connecting the trusses with said supports, a counterweight connected with the upper ends of said trusses and acting to counter-balance said door.

8. A housing device for flying machines 10 comprising an inclosing device provided with an opening through which the object to be housed may be introduced into and withdrawn from the inclosing device, a door for said opening pivoted near its upper end 15 and normally in a vertical position when closed, a portion of said door projecting beyond the pivotal point, and a counterweight connected with the projecting end of said door arranged to counter-balance the same, 20 the door when open forming a canopy over the opening.

9. A closing device for flying machine enclosures comprising one or more sections or parts mounted on pivots near one end 25 thereof, said pivots secured to the door supports, extensions beyond said pivots, counterweights on said extensions and means for rotating said sections about their pivots to open and close the sections.

30 10. A closing device for closing an open-

ing comprising a section mounted on pivots near one end, a supporting device for said pivots to which they are attached, an extension beyond said pivots, a counterweight pivoted to said extension and extending vertically above it, when the closing device is open, a link pivoted to the upper part of said counterweight at one end and to the supporting device at the other, so that the whole device is balanced, means for rotating said closing device, all parts of said closing device in its fully open position being beyond the limits of the clearance line of the opening to be closed. 35

11. A movable part adapted to be opened or closed, pivots near one end thereof on which said movable part is mounted, supports for said pivots, an extension beyond said pivots, an upwardly extending counterweight pivotally connected to said extension and counter-balancing the weight of the movable part, a link pivotally connected with the upper end of said counterweight, a support to which said link is pivotally connected, and means for rotating said movable part from one plane into another plane. 50 55

Signed at Chicago, county of Cook and State of Illinois, this 7th day of August, 1920.

JOSEPH B. STRAUSS.
